MULTIPLE BOX LOOMS

John Frederick Moseley, Heaton Mersey, Stockport, Iorwerth Hefin Thomas, Manchester, and John Joseph Vincent, Wilmslow, England, assignors to The British Cotton Industry Research Association, Manchester, England, a British research association

Application June 17, 1953, Serial No. 362,318

Claims priority, application Great Britain June 19, 1952

10 Claims. (Cl. 139—170.3)

This invention relates to multiple box looms including pick-and-pick looms.

A well-known difficulty in connection with such looms is the occurrence of "lashing in" or "dragging in," that is, the drawing into the warp shed by one shuttle of a loop or end of a thread or threads of the weft trail of another shuttle or shuttles. Such trails are only lightly tensioned and a change of position of the box inevitably leaves slack one or more of such trails lying on the shuttle race board where it, or they, can be dragged in by a shuttle itself. In particular, in the case of the circular box, such trails can become inter-twined so as to cause lashing-in when one of those threads becomes operative, while, with some types of yarn, snarls may cause entanglement, or other conditions may arise, sufficient to cause such "lashing-in."

Various mechanical devices are known for controlling the trails of the shuttles including the use of dobby jacks, but such known devices are not entirely satisfactory and are only applicable to relatively simple pattern sequences.

The object of the present invention is a simple and improved mechanical device to overcome the aforesaid difficulty.

According to the invention a device for controlling the shuttle trails in a multiple box loom comprises suction means between the selvedge and the entrance to the multiple shuttle box whereby trails from shuttles not in the picking position are kept in tension sufficient to resist "lashing-in" by the working shuttle, or by its weft, but insufficient to prevent release of such trail for correct weft insertion when the shuttle is again brought into use and also insufficient to cause weft to be drawn to waste from the shuttles.

The device aforesaid may be characterised by means for cutting the trails from shuttles, other than the working shuttle adjacent the selvedge and by location of the suction means adjacent the entrance to the shuttle box in combination with gripping means for holding the shuttle end of each trail so that the shuttle can correctly lay its weft at its next pick; or characterised in that the gripping means for holding the shuttle end of the trail comprises gripping means structurally combined with the suction device; or characterised by means for providing the suction intermittently and synchronised to operate during the required part or parts of each loom cycle; or characterised by means for providing the suction and action of the gripping means intermittently and synchronised to operate during the required part or parts of each loom cycle; or further characterised by means for holding, clear of the shed, the cut ends left at the selvedge of the cloth.

In the accompanying drawings:

Fig. 1 is a fragmentary perspective view of one side of a loom showing one example of a device made in accordance with the invention.

Fig. 2 is a detail perspective view of the suction nozzle shown in Fig. 1.

Fig. 3 is a fragmentary perspective view showing another example of the invention.

Fig. 4 is a perspective view showing that part of the

2

mechanism immediately adjacent the selvedge of the cloth.

Fig. 5 is a perspective view showing in detail the suction chamber as fitted to the shuttle raceboard adjacent the entrance to the circular box as can be seen in Fig. 3.

Figs. 6 and 7 are plan and elevation of the suction chamber and valve shown in Fig. 5.

Figs. 8 and 9 are plan and elevation of the weft trail cutter.

Figs. 10 and 11 are diagrammatic plan and elevation showing the essential parts of the loom relative to the weft trail cutter.

In the example of the invention shown in Figs. 1 and 2, above the sley race *a* and close to the loom temple *b* is a suction nozzle *c* held adjustably in a clamp *d* so that it can be adjusted laterally towards or away from the loom temple, or moved forwards and backwards as may be found to be the best position. The working shuttle is assumed to be at the other end of the loom out of sight and weft trails *e*¹, *e*², *e*³, *e*⁴ and *e*⁵ are shown leading from the nozzle *c* to the entrance of the rotary shuttle box *f*. All five trails are shown at *e* between the nozzle and the adjacent selvedge and are not necessarily in the same order as between the nozzle and the shuttle box. These weft trails are held in light tension, the slack between the entrance to the circular box and the selvedge, inevitably produced by the to-and-fro movement of the sley or any other cause such as rotation of the box, is instantaneously taken up by being sucked into the nozzle and is therefore held under tension and some will be held away from the run of the shuttle. Tension of the weft trails is dependent upon the intensity of suction at the nozzle and this is adjustable by means of a sleeve *c*¹, operably associated with an aperture *c*². The sleeve may be adjusted to give the suction at the nozzle most suitable for the counts and type of the weft yarn in use, so that an effective tension thereon is maintained without drawing more weft from the shuttle. When the shuttle is used again the said slack is withdrawn from the suction tube and loops are formed up the selvedge in known manner but without risk of lashing-in.

In the example of the invention as shown in Figs. 3 to 11 as applied to a circular box loom having a circular box *f*, at one side and a single box (not shown) at the other side so that the operative period is for two picks or a multiple of two picks, a suction chamber *g* is inlaid into the raceboard *a* adjacent to the entrance to the multiple shuttle box and having a single aperture *g*¹ across the entrance to the circular box with the edge *g*² of the aperture nearer the entrance to the circular box slightly below the level of the raceboard. Weft trails after cutting are shown at *e*¹, *e*², *e*³ and *e*⁴, disappearing into the aperture *g*¹. The weft trail of the last shuttle is shown at *e*⁵ from the selvedge to the shuttle box. The trail *e*⁵ shown in Fig. 3 is about to be severed and such severance will occur at about the time the shuttle reaches the far box so as to open the valve, and the severed end will be drawn into the aperture *g*¹. The new trail *e*⁶ will take the place of *e*⁵ after the next beat up and will in turn be severed at the same point in the cycle as *e*⁵ but two picks later.

As shown in more detail in Figs. 6 and 7, a single exit tube *h* is provided to the suction chamber as near as possible to the suction aperture and in the side of such exit tube is a housing *h*¹ forming an opening in which is movably located the head end *i* of a combined gripping lever and valve which is pivoted on a stud *i*¹ and moves in an arcuate path, such head end being shaped to bear against part of the internal wall of the tube *h* so as at the same time to grip any weft trail lying therein and to close off the suction under the action of a spring *i*². The operative face of the tube, that is the face against which a thread would be pressed by the leading edge of

the head end *i*, is provided with an insert *h*⁴ of rubber or other suitable material, having its face slightly set back to avoid possibility of the threads being stopped or building up at the edge. Alternatively, the end of the gripper may be rubber faced. In this example, as in the case of Figs. 1 and 2, the suction tension of the trails before cutting must be within reasonable limits and this is adjustable by means of a collar *h*² adjustable relative to an aperture *h*³.

The gripping lever is appropriately connected to the check strap *j* by a yieldable spring *k* and cord *m* so as to be moved to the open position when a shuttle enters the box at the opposite side of the loom and pulls the check strap. When the shuttle leaves the said box at the opposite side of the loom the check strap moves sufficiently to allow the lever to close off the suction under the action of the spring *i*² attached to the lever. This spring is adjustable by means of the collar *i*³ to vary as may be necessary, the pressure exerted on the yarn trapped between the gripping lever and the wall of the tube.

As shown in Fig. 4 a weft trail cutter is secured by its body *n* to the outer face of the loom temple *b*, as shown in Figs. 8 and 9 in the body *n* is slidably mounted a bar *o* in the end of which is secured a cross sleeve *o*¹ at the selvedge end of which is fixed the stationary part *p* of a rotary cutter. The rotary part *p*¹ of the cutter is carried by a spindle *p*² slidably and rotatably mounted in the sleeve. At the other end of the sleeve is a gear pinion *p*³ secured by a collar *p*⁴ and pin *p*⁵; a spring *p*⁶ on the sleeve serving to maintain the rotary part *p*¹ effectively urged into facial contact with the stationary part. On the lower part of the outer face of the body *n* is fixed a cam plate *n*¹ having a cam hole *n*². Above such cam plate, the body *n* is slotted and through such slot projects a boss *o*² on the bar *o* in which is fixed a headed spindle *o*³ carrying a gear segment *o*⁴ complementary to the pinion *p*³. In the segment *o*⁴ is a pin *o*⁵ complementary to the cam hole *n*². The outer end of the bar *o* is bifurcated at *o*⁶ to form coupling means for a link *s*⁴ described later with reference to Figs. 10 and 11.

In operation, the bar *o* is adapted to be reciprocated by cam means shown in Figs. 10 and 11 its normal position being as shown in Figs. 8 and 9 with the pin *o*⁵ at the right hand lower end of the cam hole. The pin is marked with a 4 to indicate that it is in the fourth position of the cycle of movement. When the rod is moved to the left of Figs. 8 and 9 it carries the cutter rearwardly to follow up the shuttle race as the sley moves rearwardly. By the time the working shuttle has left the circular box, any weft trails stretching from the selvedge of the suction box will be located in the working opening of the cutter formed by the fixed and rotatable parts thereof and the pin *o*⁵ will be in the dotted position 1 at the left hand lower end of the cam hole. Such weft trail will be in tension due jointly to the immediately preceding movement of the circular box and the backward movement of the sley so that the risk of lashing-in, immediately after shuttle change, is negligible. The risk increases enormously at the next pick from the circular box because, if there has been no further movement of the circular box to take up weft trail slack, the working shuttle, or its weft is liable to catch this slack weft trail causing "lashing-in." With the present invention the weft trail is cut immediately after each shuttle change. Further movement of the bar *o* to the left causes the quadrant to be turned, the pin rising at the same time to the dotted position 2 in the cam hole. Rotation of the quadrant by its engagement with the gear pinion rotates the cutter part *p*¹ to effect severance of any weft trails in the cutter. As by that time the working shuttle will have drawn any slack of its weft into the warp shed so that it cannot be severed by the cutter. The cutter is withdrawn forwardly by the bar *o* before

the sley returns for the beat up so that it is not in the way of the reed.

In Figs. 10 and 11 are shown diagrammatically the essential parts of the loom relative to the weft trail cutter of Figs. 8 and 9 and its operation. The sley carrying the shuttle raceboard *a* is reciprocable in known manner. Attached to the side of the loom adjacent the bottom shaft *q* is a lever *r* in engagement with a cam *q*¹ on the bottom shaft the end of such lever *r* is connected by cable *r*¹ to an actuating assembly mounted at the front of the loom and comprising a bracket *s* carrying a guide pulley *s*¹ for the table *r*¹ and also carrying a spindle to the lower and upper ends of which are secured arms *s*² and *s*³ the latter being connected by link *s*⁴ to the bar *o* at *o*⁶. The cable *r*¹ is attached to the arm *s*² which also has a return spring *s*⁵ secured to it and to the front of the loom. The cam *q* is proportioned and timed to move the cutter by its bar *o* as above explained relative to the movement of the sley, a spring *r*² serving to keep the lever *r* engaged with the cam.

In operation at any instant before cutting, the shuttle trails from the selvedge will normally be lying across the suction aperture and immediately after the weft trail is cut near the selvedge of the cloth this trail extending from the eye of the shuttle is sucked down the aperture the next time a shuttle arrives in the opposite box because the check strap *j* will be moved by any shuttle to move the gripper head *i* and open the suction passage.

Whenever the gripper is closed all shuttle trails in the exit tube will be held so that the shuttle having its trail so held can correctly lay the weft at its next pick. The weft is left between the orifice and the selvedge and a few picks later will be severed, part being sucked down the orifice while part remains as a fringe at *t* as shown in the drawings. Any slack occurring in a trail until cut due to movement of the sley and box will of course be taken up pneumatically. Obviously the gripper is released and the suction applied each time there might be a shuttle weft trail to be disposed of, that is each time the working shuttle reaches the opposite shuttle box.

The sequence of operation is therefore:

1. Cutting at selvedge;
2. Suction acts to remove trail;
3. Securing or gripping the trail;
4. Picking by the shuttle having its trail secured or gripped.

Preferably, the raceboard between the selvedge and the suction box is smooth and polished to allow free movement of the trails. A small projection *g*³ is provided at the back of the suction chamber to prevent the weft trails from slipping between the chamber and the box flap.

Further suction means may be provided at the selvedge to draw the short ends away from the shed and avoid their being dragged in.

Obviously, when using suction without cutting, the most convenient position for the suction device is near the selvedge where there is the least lateral movement of the wefts with the change of position of the box.

What we claim is:

1. In a multiple-box loom, in combination, warp holding means for holding warps in a position in which a fabric is formed with a selvedge thereof located in a predetermined plane defined by said warp holding means; a multiple shuttle box located spaced from said predetermined plane; a plurality of shuttles arranged in said multiple shuttle box, each of said shuttles adapted to hold a weft, said shuttles being operated in a predetermined sequence so that at least one of said shuttles remains inactive in said multiple shuttle box while at least one other of said shuttles passes out of said shuttle box during a weaving operation; and suction means located intermediate said multiple shuttle box and said predetermined plane and adapted to attract by suction wefts held by said shuttles with such force as to hold the weft of

said at least one inactive shuttle tensioned but to release the weft of said at least one other shuttle during a weaving operation.

2. In a multiple-box loom, in combination, warp holding means for holding warps in a position in which a fabric is formed with a selvedge thereof located in a predetermined plane defined by said warp holding means; a multiple shuttle box located spaced from said predetermined plane and having an entrance opening; a plurality of shuttles arranged in said multiple shuttle box, each of said shuttles adapted to hold a weft, said shuttles being operated in a predetermined sequence so that at least one of said shuttles remains inactive in said multiple shuttle box with the thread associated therewith passing through said entrance opening while at least one other of said shuttles passes through said entrance opening out of said shuttle box during a weaving operation; and suction means located intermediate said entrance opening of said multiple shuttle box and said predetermined plane and adapted to attract by suction wefts held by said shuttles with such force as to hold the weft of said at least one inactive shuttle tensioned during a weaving operation; and gripping means for holding the weft associated with said at least one shuttle.

3. In a multiple-box loom, in combination, warp holding means for holding warps in a position in which a fabric is formed with a selvedge thereof located in a predetermined plane defined by said warp holding means; a multiple shuttle box located spaced from said predetermined plane and having an entrance opening; a plurality of shuttles arranged in said multiple shuttle box, each of said shuttles adapted to hold a weft, said shuttles being operated in a predetermined sequence so that at least one of said shuttles remains inactive in said multiple shuttle box with the thread associated therewith passing through said entrance opening while at least one other of said shuttles passes through said entrance opening out of said shuttle box during a weaving operation; suction means located adjacent said entrance opening of said multiple shuttle box and said predetermined plane and adapted to attract by suction wefts held by said shuttles with such force as to hold the weft of said at least one inactive shuttle tensioned during a weaving operation; and gripping means for holding the weft associated with said at least one shuttle.

4. In a multiple-box loom, in combination, warp holding means for holding warps in a position in which a fabric is formed with a selvedge thereof located in a predetermined plane defined by said warp holding means; a multiple shuttle box located spaced from said predetermined plane and having an entrance opening; a plurality of shuttles arranged in said multiple shuttle box, each of said shuttles adapted to hold a weft, said shuttles being operated in a predetermined sequence so that at least one of said shuttles remains inactive in said multiple shuttle box with the thread associated therewith passing through said entrance opening while at least one other of said shuttles passes through said entrance opening out of said shuttle box during a weaving operation; suction means located adjacent said entrance opening of said multiple shuttle box in said predetermined plane and adapted to attract by suction wefts held by said shuttles with such force as to hold the weft of said at least one inactive shuttle tensioned during a weaving operation; and gripping means fixedly connected to said suction means for holding the weft associated with said at least one shuttle.

5. In a multiple-box loom, in combination, warp holding means for holding warps in a position in which a fabric is formed with a selvedge thereof located in a predetermined plane defined by said warp holding means; a multiple shuttle box located spaced from said predetermined plane and having an entrance opening; a plurality of shuttles arranged in said multiple shuttle box, each of

said shuttles adapted to hold a weft, said shuttles being operated in a predetermined sequence so that at least one of said shuttles remains inactive in said multiple shuttle box with the thread associated therewith passing through said entrance opening while at least one other of said shuttles passes through said entrance opening out of said shuttle box during a weaving operation; suction means located adjacent said entrance opening of said multiple shuttle box and said predetermined plane and adapted to attract by suction wefts held by said shuttles with such force as to hold the weft of said at least one inactive shuttle tensioned during a weaving operation; gripping means for holding the weft associated with said at least one shuttle; and means for providing suction in said suction means and for operating said gripping means intermittently and synchronized in a predetermined sequence with each cycle of a weaving operation.

6. In a multiple-box loom, in combination, warp holding means for holding warps in a position in which a fabric is formed with a selvedge thereof located in a predetermined plane defined by said warp holding means; a multiple shuttle box located spaced from said predetermined plane and having an entrance opening; a plurality of shuttles arranged in said multiple shuttle box, each of said shuttles adapted to hold a weft, said shuttles being operated in a predetermined sequence so that at least one of said shuttles remains inactive in said multiple shuttle box with the thread associated therewith passing through said entrance opening while at least one other of said shuttles passes through said entrance opening out of said shuttle box during a weaving operation; suction means located adjacent said entrance opening of said multiple shuttle box and said predetermined plane and adapted to attract by suction wefts held by said shuttles with such force as to hold the weft of said at least one inactive shuttle tensioned during a weaving operation; cutting means for cutting the weft from said at least one shuttle; and gripping means for holding the weft associated with said at least one shuttle.

7. A device according to claim 6 and including means for withdrawing and holding clear of said warps the cut ends left at the selvedge of the fabric.

8. In a multiple-box loom, in combination, warp holding means for holding warps in a position in which a fabric is formed with a selvedge thereof located in a predetermined plane defined by said warp holding means; a multiple shuttle box located spaced from said predetermined plane and having an entrance opening; a plurality of shuttles arranged in said multiple shuttle box, each of said shuttles adapted to hold a weft, said shuttles being operated in a predetermined sequence so that at least one of said shuttles remains inactive in said multiple shuttle box with the thread associated therewith passing through said entrance opening while at least one other of said shuttles passes through said entrance opening out of said shuttle box during a weaving operation; suction means located adjacent said entrance opening of said multiple shuttle box and said predetermined plane and adapted to attract by suction wefts held by said shuttles with such force as to hold the weft of said at least one inactive shuttle tensioned during a weaving operation; cutting means for cutting the weft from said at least one shuttle; gripping means for holding the weft associated with said at least one shuttle; and means for providing suction in said suction means and for operating said gripping means intermittently and synchronized in a predetermined sequence with each cycle of a weaving operation.

9. In a multiple box loom in combination with a plurality of shuttles which are operated and inactive in a predetermined sequence, a suction means for tensioning weft trails associated with inactive shuttles.

10. In a shuttle loom for weaving a fabric with a selvedge and having a multiple compartment box for holding a plurality of shuttles one in each compartment

adapted for use selectively through a common shuttle box entrance according to a predetermined pattern so that at least one weft trail will normally extend from a shuttle in a compartment of such box through the common entrance to the selvedge while another shuttle from another compartment is being used for weaving and is passing through such common entrance, comprising in combination a suction nozzle located in the path of such weft trail between the selvedge and the said common entrance, and means connecting such nozzle to a source

of suction whereby a weft trail from a shuttle in a waiting position in the box and leading from the common entrance to the selvedge is tensioned by such suction device.
